25 Claims. (Cl. 209—144)

1

This invention relates to apparatus for separating particles from a fluid by rotating the mass of fluid and particles in a separating chamber. More particularly, the invention has reference to a novel centrifuge for this purpose which affords improved results, as compared with prior centrifuges, by reason of its inclusion of a helical worm so arranged in the separating chamber that it coats with the rotating mass to discharge the particles separately from the fluid.

As the invention may be used to particular advantage for separating dust or other particles from a gas, for example, to purify the gas, it will be described herein as a gas centrifuge. It will be understood, however, that the invention is not limited to such use.

Cyclones are constructed so that the axis of rotation of the gas mass will be vertical, and the particles separated from the gas are discharged from the separating chamber in such a way that, due to the force of gravity, they will settle to the bottom of the cyclone where they are collected. This method of discharge sets a limit to the applicability of such cyclones, owing to the fact that the particles most difficult to separate, and which are separated out in the vicinity of the gas outlet, have low falling speeds, thus being easily sucked away by the escaping gas. The separating power of a cyclone cannot, therefore, be raised very much, as the highest angular speeds cannot be utilized.

The present invention, therefore, is directed to the provision of an improved centrifuge which eliminates the disadvantage above mentioned and which, in addition, provides other advantages unobtainable with prior apparatus of this character. As in the case of cyclones, the new apparatus discharges the particles in the axial direction. However, this discharge is effected forcibly by a worm shaped as a spiral spring and specially adapted for the purpose, the worm being preferably rotated on an axis coinciding with the longitudinal axis of the rotation-symmetrical separating chamber. The operation may be readily controlled by proper adjustment of the relation between the angular speeds of the gas and of the worm in the separating chamber at the radius where a certain discharge speed is desired. In order that the friction against the worm shall not unnecessarily reduce the angular speed of the gas, the worm is preferably caused to rotate in the same direction as the gas in the separating chamber.

For a more complete understanding of the invention, reference may be had to the following

2

description, taken in conjunction with the accompanying drawings in which

Fig. 1 is a sectional view of one form of the new apparatus, the section extending along the axis of rotation on the line 1—1 in Fig. 2;

Fig. 2 is a sectional view on the line 2—2 in Fig. 1, with parts broken away;

Fig. 3 is a sectional view similar to Fig. 2 but enlarged and showing only the manner of mounting an inner supporting ring for the worm on its rotating shaft;

Fig. 4 is a view similar to Fig. 3 but showing an alternative supporting arrangement for the worm;

Fig. 5 is a perspective view of still another arrangement for supporting the worm on the shaft, and

Figs. 6 to 11, inclusive, are sectional views taken along the axis of rotation, showing parts of modified forms of the apparatus.

In the following description, the expression "direction of displacement" is intended to denote the direction in which the particles are provided with an axial movement in the separating chamber by the relative movement between the rotating gas and the worm.

The mode of operation of the separator depends upon the variable relative speeds of the gas and the worm. The inlet speed of the gas immediately beyond the inlet to the separating chamber is changed to peripheral speed of the gas rotation in the chamber so that this inlet speed will determine the angular speed, i. e. the separating power and the counter-pressure.

If the peripheral speed of the gas at the outer edge of the worm is lower than the speed of the worm at its outer edge, the gas is displaced thereby the worm in an axial direction which depends upon the direction of the worm thread. If the inlet speed of the gas is increased, and assuming the rate of rotation of the worm to be unaltered, the speed of discharge is diminished; and the discharge ceases when the angular speeds of the gas and of the worm are equal. In case the gas speed

is further increased, the direction of discharge is reversed. During its movement toward its outlet, which is nearer the axis of rotation than the inlet, the gas will be rotating more quickly, while the angular speed of the worm remains constant. This fact accounts for two instances of gas movement which can be distinguished.

In the first instance, the worm rotates everywhere at a higher angular speed than the gas, i. e. even at the smallest radii, and the speed of discharge of the particle decreases with reduced ra-

dial distance from the axis of rotation. The direction of movement for such gas particles as will enter at the side surfaces of the gas inlet, is indicated by dotted arrows in Fig. 7.

In the second instance, when the peripheral speed of the gas is greater than that of the worm at its outer edge, the relative movement will increase the more the gas is approaching the outlet. The direction of discharge is here the reverse of that in the former case, and the discharge speed increases towards the outlet. The gas particles will thus move according to the dotted arrows in Fig. 6.

In a transitional instance, the peripheral speed of the worm is greater than that of the gas at the inlet, but smaller than that of the gas at the outlet. The discharge direction of the particles is then changed at a certain radial distance from the axis, and it will be understood that in this case easily separated particles will be discharged in the one direction at great radii, and particles difficult to separate will be discharged in the opposite direction at small radii.

The gas separator illustrated in Figs. 1 and 2 operates according to the aforementioned transitional case. It comprises a separating chamber 1 surrounded by a pipe 2 which, in turn, is surrounded by a housing 3. In the space 37 between the latter, the gas is introduced. The pipe 2 is provided with one or more generally rectangular orifices 4 extending between walls 5b and 5d which constitute the side surfaces of the gas inlet. The pipe 2 is rotatable so that the slot 6, which is limited by the housing 3 and an edge of the pipe defining the orifice 4, can be made narrower or wider. By this or any other arrangement having the same effect, it is possible to change the tangential inlet speed of the gas at a certain capacity, or change the capacity for constant inlet speed. This adjustment may be made in the course of the separation, by any suitable means (not shown), such as an adjustment handle outside the housing for rotating the pipe 2.

In the separating chamber 1 is the worm 7 which brings about the axial discharge. The separate gas leaves the separating chamber 1 at the inner edges of the worm 7 at both ends of the separating chamber, and passes between the worm shaft 8 and pipes 9a and 9b, respectively, to gas discharge chambers 10a and 10b. Secured to each side of the housing 3, that is, near each end of the separating chamber 1, are side pieces 11a and 11b providing sludge spaces 12a and 12b as well as the gas discharge chambers 10a and 10b, respectively, the side pieces serving also to support bearings 13a and 13b for the worm shaft 8. The bearings may, if desired, be supported by elastic and/or shock-absorbing elements, such as rubber rings 14 or buffers, like the top bearings of separators.

The worm 7 is provided at its ends with covers 15a and 15b, respectively, the outer sides of which may also serve as ventilator wheels. The sludge or dust discharged by the worm is brought to the right (Fig. 1) at the radii where the peripheral speed of the worm is greater than that of the gas, if the right-hand threaded worm is rotating in the direction of the arrow. At smaller radii, where the peripheral speed of the worm is less than that of the gas, the dust is discharged in the opposite direction. When the dust has reached the covers 15a and 15b, it is conveyed to the corresponding sludge spaces through slots 17a and 17b, respectively. As shown, the slot 17a is

formed between the outer edge portion of cover 15a and a ring 19a on the worm, while the slot 17b is formed at the inner edge portion of cover 15b between the latter and the hub of an adjacent cover 18. In order to facilitate this radially directed movement, the slot 17b may serve as an inlet to a fan formed by vanes 18b between the covers 15b and 18, and the slot 17a may serve as an outlet from a fan formed by vanes 18a between the edge of the ring 19a and the cover 15a.

The separated gas is led away through diffusor-like outlets 33a and 33b at opposite ends of the worm. The speed of the discharging gas can thus be reduced, the kinetic energy of the gas then being transformed into pressure. The diffusors 33a and 33b may be spiral-shaped if desired, it being understood that their purpose is to transform energy of rotation as well as energy emanating from the axially directed movement of the gas, into pressure energy.

The worm 7 is supported by outer supporting rings 19a and 19b, and by inner supporting rings formed by the pipes 9a and 9b and an intermediate pipe 9c, which are centered in relation to the shaft 8 by spokes or wings 20 connected to the shaft. The outer supporting rings 19a and 19b may be provided with internal grooves into which the outer edges of the worm are threaded and/or fixed, as by soldering or welding. In order that the spokes or wings 20 shall cause as little resistance as possible to the gas flow, they may be made of steel wire or of thin plate, or they may be stream-line shaped, thus offering little resistance to an axially directed flow and/or a rotational flow. As shown in Fig. 3, six spokes or wings 20 are formed by U-shaped plates 20a fitted at their intermediate portions in longitudinal slots in the shaft 8, the sides of adjacent plates converging and being secured at their ends to the inner supporting ring for the worm. In the modification shown in Fig. 4, three spokes are provided by a triangular plate 20b fixed to the shaft 8a, the corners of the plate being secured to the inner supporting ring.

In operation, a certain difference in pressure will always prevail between the gas discharge chambers 10a, 10b and the sludge spaces 12a, 12b. The pressure in the sludge spaces is equal to the difference between the initial pressure of the in-going gas in the space 37 and the "head" obtained immediately beyond the inlet slot 6. In the central parts of the gas discharge, i. e. in the inlet of the diffusors 33a and 33b, a low pressure (subatmospheric) prevails, the magnitude of which depends upon constructional details as well as upon throughput rate and inlet pressure. The high speeds of the gas, mainly directed tangentially in the plane of rotation and which cause this low pressure, are reduced in the diffusors 33a and 33b and are thus transformed into pressure. Accordingly, if the gas were able to pass through the separator without loss, the final pressure of the gas in the outlet 10 would be the same as its initial pressure.

The wings 20 in the gas outlet pipes 9a and 9b may be shaped in such a way as to transform the gas energy into mechanical work which is absorbed by the rotor shaft 8, or suitable turbine devices in the gas outlet may serve this purpose. In such a case, the pressure in the gas discharge chambers 10a and 10b will naturally be lower the more energy is taken from the gas by these means.

Ignoring such an energy transformation by

wings or blades, and assuming that a slit 32 is formed between the rotor and the stationary part of each diffusor 33a, 33b at its inner portion, as shown in Fig. 1, a higher pressure will always prevail in the sludge spaces 12a, 12b than at these slits. Consequently, it is necessary to provide means for preventing dust-mixed gas from leaking out through the slits from the sludge spaces to the discharging purified gas. Instead of the usual type of tightening or sealing means for such purposes, a ventilator or turbine may be used, or any other device which can overcome this drop in pressure. If the device affords a somewhat higher difference in pressure between its inlet and outlet than exists between the sludge space 12a or 12b and the slit 32, a certain limited quantity of pure gas may escape through the slit from the gas outlet to the sludge space 12a or 12b. In the embodiment of the invention shown in Fig. 1, the tightening devices are constituted by fan wheels 16a and 16b on the rotor.

As the fans 16a and 16b are to create a pressure equal to or somewhat greater than the pressure fall in the separating chamber 1, their rate of rotation must increase if this pressure fall increases. The rate of rotation of the fans, i. e., of the rotor, therefore depends upon the initial pressure of the gas being separated, upon the gas speed in the inlet slot 6, and upon the throughput rate. If desired, the use of the tightening fans 16a and 16b may be avoided by locating each slit 32 at a part of the diffusor in which the pressure has become as great as or somewhat greater than that in the sludge space 12a or 12b, as shown at 32a in Fig. 9. As friction losses cannot be avoided, it is necessary that the diameter of the slit 32a be greater than that of the worm, if the pressure at the slit is to be identical with or greater than the pressure in the sludge space. The slit 32a may be dimensioned and located in this manner by modifying the diffusor as shown at 33c (Fig. 9), the modification including an outwardly flared end piece 39a secured to and forming a continuation of pipe 9a.

By changing the inlet speed of the gas through slot 6, the speed and direction of the discharge may be controlled. The operation of the separator shown in Fig. 1 is such that easily separated particles are discharged to the right in the outer portion of the separating chamber 1 and escape to the sludge space 12a through the slits 22a and 17a. Lighter particles are separated nearer to the axis of rotation and are discharged to the left (Fig. 1).

They escape through the slit 17b to the sludge space 12b. Thus, the separator not only rids the gas of dust but also separates more and less easily separated particles from each other and leads them to different sludge spaces. By properly controlling the inlet speed of the gas in relation to the angular speed of the worm 7, it is possible, therefore, to distribute the dust particles at will, according to their separability, between the sludge spaces 12a and 12b.

The invention is not limited to the form shown in Fig. 1 but may, for example, take either of the forms shown in Figs. 6 and 7. The separator illustrated in Fig. 6 is intended for large throughputs. Because of strength factors, the rotational speed of the worm 7 is limited and reduced, the greater its diameter is made. Accordingly, if a high degree of separation is desired at a large throughput rate, it is preferable to choose a speed of the ingoing gas which is higher than the peripheral speed of the worm. All of the out-sepa-

rated particles will then move in the same axial direction, although at varying speeds, and are collected in a number of generally annular slits 23 formed in a cover 23a rotating with the worm. In Fig. 6, only three slits 23 are shown, in order to simplify the disclosure. The out-separated particles are conveyed to the sludge space 12 through fans or ventilators 24. If all of the fans 24 (Fig. 6) open into a common sludge space, they must have varying outer diameters or in any case be so designed that their outlet pressures will be nearly equal. For practical reasons, the fan 24 having its inlet nearer to the shaft 8 is dimensioned so as to give a somewhat higher outlet pressure than the next fan, the gas inlet of the latter being situated on a greater radius. This reduces the risk of particles difficult to separate being exposed to such gas speeds as may cause previously separated particles to be blown into the gas outlet. Should the outlets from slits 23 open into different sludge spaces, the latter can be tightened or sealed from each other in any suitable manner. The outer diameters of the fans 24, in a separator of this type, should generally be greater than that of the worm 7.

In the Fig. 6 embodiment, the pitch of the worm thread preferably decreases toward the gas outlet (to the left in Fig. 6) so that the discharge speeds are reduced in the parts of the separating chamber 1 located closer to the particle outlets 23. The length of the worm may also be reduced in this manner. At the opposite end of the worm, where no particle discharge takes place, the final turn of the worm is suitably fixed and centered, this final turn being in a plane at right angles to the rotating shaft at a cover 25. The cover 25 is shaped and fixed to the shaft 8 in such a way that the cover also serves as support for radially directed forces and for turning and bending moments. The worm is surrounded by a tube 26 at the side of the gas inlet near the particle outlets 23, and opposite the gas inlet the inner edge of the worm is fixed to a tube 27. The separator parts may be so dimensioned and arranged that the tube 27 extends partly into the tube 26, whereby these tubes include between them more than one thread of the worm, preferably more than two threads. Thus, each tube is rigidly fixed to the other, so that the whole rotor will be resistant to the forces incident to operation of the separator, especially to transverse forces of inertia.

The embodiment shown in Fig. 7 is adapted primarily for small capacities. The peripheral speed of the worm 7 in this instance is considerably greater than the inlet speed of the gas so that, if the direction of the worm rotation and of the worm thread is the same as in Figs. 1 and 6, the gas will move to the right in Fig. 7. Also, in this instance the discharge speed decreases as the gas approaches the outlet. The particles escape to the sludge space 12c through slits 28 and fans or ventilators 29 formed in a cover 28a rotating with the worm at the right-hand end thereof. Otherwise, the separator is in principle like that shown in Fig. 6. It may be desirable in the Fig. 7 embodiment to increase the pitch of the worm toward its right-hand end located nearer to the outlet. As the fans 29 rotating with the worm (especially at the large radii) have a considerably greater angular speed than the gas, they can be made with an external diameter smaller than that of the worm. The external diameters of the fans 29 may decrease the nearer to the axis of rotation their inlets are located.

The discharge of the particles in the separating chamber 1 in directions toward the covers 15a and 15b (Fig. 1) presupposes that the gas has at the same time an axial movement. As the separated gas near the covers flows centrally in its discharge, i. e. in a direction toward the shaft and not parallel with it, care must be taken that gas from the sludge spaces 12a, 12b circulates at the ends of the separating chamber. On the side of the cover 15a facing the separating chamber are ventilator vanes 18a (not absolutely necessary), which produce at the inner edge of the ring 19a a pressure higher than that of the gas being separated at the same radius. Therefore, gas will be fanned out through the slit 17a to the sludge space 12a and pass back from there, at about the outer radius of the separating chamber, through the slit 22a. When entering the slit 22a, the gas has a low speed of rotation and is therefore caused to move towards the cover 17a by the worm. Gas will thus circulate around the ring 19a, and it is important for the proper functioning of the separator that the gas escaping outwards through the slit 17a has a higher particle content than the gas entering through the slit 22a. This may be the case without any special arrangements being provided, but fulfillment of this condition may be assured by introducing a filter in or near the slit 22a (for instance, a cloth, a net, or the like) allowing the gas but not the particles to pass through it. The same arrangement may, of course, be used at the slit 22b as well.

In order to ensure that the gas has sufficient angular speed when passing through the slit 22a, and as high a speed as possible after passing through the slit 22b, it may be desirable to provide a system of wings in these slits. Thus, the slit 22a may be provided with a system of suitably shaped wings or blades, either stationary or rotating with the rotor. The air passing through the slit 22b may be introduced by similar means to obtain the desired speed as it enters the separating chamber.

The wings as well as the filters above mentioned may be incorporated in the separators shown in Figs. 6 and 7. In Fig. 6, I have shown rotating wings 30 in the outlet slit from sludge space 12, and in Fig. 7 I have shown stationary wings 31 in the outlet slit from the sludge space 12c.

During its passage through separating chamber 1 from the inlet to its outlet, a gas particle moves along a surface of rotation whose shape is determined by the pitch and rotational velocity of the worm, and by the gas speed. Gas particles entering at the two end surfaces of the inlet 6, that is, at the surfaces or edges extending parallel to the shaft 8 and along the inlet, will move along such surfaces of rotation whose shape, however, will differ somewhat from that of other particles, due to the friction against gas masses located at the periphery of the separating chamber proper, and against rotor parts. By the separating chamber proper is meant that portion of the chamber 1 located between the two extreme or limiting surfaces of rotation along which particles from these two end surfaces of the gas inlet are moving. If the gas is considered as moving without friction, its angular speed outside this separating chamber proper will be constant, but within this chamber the gas particles will be moving at different angular speeds. A great difference in speed between these gas masses may cause certain difficulties in the discharge of the particles, but these difficulties may

be avoided by discharging the particles exactly at these limit surfaces of rotation, as in the embodiments shown in Figs. 10 and 11.

In Fig. 10, I have shown part of a worm 1a, one end portion of which is surrounded by a shell 26 fitting tightly to the outer edges of the worm surfaces, the shell being shaped according to the limit surface. The shell 26 is provided at different radii with annular slots 34 forming outlets for the separated particles and which, as in the embodiments of Figs. 6 and 7, form the inlets to discharge fans 35 for the particles entering the sludge space 12d.

Instead of providing the particle outlet slots in the shell 26, they may be formed in the worm by making the worm surfaces double, as shown at 1b in Fig. 11. Near the end of the worm, the internal surface of the worm facing the direction from which the discharge is effected has a spiral-shaped slot 36 extending along the above-mentioned limit surface of rotation. In other words, the slot 36 has a gradually decreasing radius from the axis of rotation as it extends along the worm toward the direction of discharge, and the slot serves as an outlet for the particles leading into the outwardly facing space between the double walls of the worm. In this outwardly facing space between the two worm surfaces lying closer together are wings 35a between which the particles are transported to the sludge space 12e. The radial distances from the shaft to the outer edges of these wings, which thus act to discharge the particles, preferably vary in the same manner as in the ventilators 24 and 29 shown in Figs. 6 and 7. It will be apparent that in the Fig. 11 embodiment, instead of enclosing the separating chamber proper in a shell as shown in Fig. 10, the shell is in effect arranged at the outer edges of the worm. The outlines of the shell and of the limit surface may then differ from each other, as shown in Fig. 11.

The discharging gas has a great kinetic energy which may be utilized and transferred to the shaft 8 by the use of turbine arrangements at the gas outlet. The spokes 29 may for that purpose be shaped as turbine blades. Moreover, special turbine arrangements rotating with the shaft 8 may be provided at the gas outlet, for example, as shown in Fig. 8. These turbine arrangements may comprise two or more series of turbine blades including stationary guide blades 40 and adjacent rotating blades 41, the blades being arranged radially in planes at right angles to the shaft, and also obliquely to such planes, or cylindrically. Thus, if the fan or compressor supplying the separator with gas of the required pressure is coupled to the rotor shaft 8, its power consumption will be considerably reduced because of the turbine arrangements.

In order to obtain a good separation with the new apparatus, it is important that the gas move as freely as possible in the separating chamber. Accordingly, the worm should always be extended a certain minimum length in the direction of feed reckoning from the side surfaces of the gas inlet 6, that is, from the inlet surfaces nearest the side pieces 11a, 11b. The covers 23a and 28a in Figs. 6 and 7, and the covers 15a and 15b in Fig. 1, must therefore be located at such distances from the inlet 6 that they do not intercept the main paths of flow of the gas to the gas outlets (do not intersect the dotted arrows in Figs. 6 and 7). It appears that the minimum length indicated should be at least as great as the height of

the worm measured radially, i. e. the difference between the outer and inner radii of the worm.

It will be observed that the length of the separating chamber proper is not greater than the width of the gas inlet 6 between the limit surfaces 5a and 5b (Fig. 1). The radial gas speeds will decrease as this chamber is made wider, and consequently a higher degree of separation will be obtained. The minimum length of the worm is determined principally by the width of the gas inlet 6 and is limited only by requirements of physical strength. The practical lower limit for the length of the worm will generally correspond to a measure somewhat smaller than its outer diameter.

The relation between the outer and the inner radii of the worm should be low for several reasons. A great radius ratio means among other things a large outer diameter of the worm, whereby the rate of rotation of the worm must be kept low because of strength factors. Also, the increase in speed of the gas in the separating chamber becomes very great, so that with a large radius ratio the inner friction of the gas may cause great losses of energy. Furthermore, the worm would have to be relatively long, involving mechanical difficulties in construction.

If, on the other hand, the radius ratio of the worm is too small, there is a risk that the rotation in the separating chamber will not have time to become fully developed, due to the difficulty in bringing about a completely tangential and "shock-free" introduction of the gas. It appears that radius ratios between 1 to 1.5 and 1 to 6 are particularly favourable and that values above 1 to 10 and below 1 to 1.2 are unsuitable.

An excessively great pitch of the worm will provide too great a discharge speed. This discharge speed should be less than the tangentially directed peripheral speed of the gas, for if they are of the same magnitude, great shock losses may ensue at the inlet 6. As a general rule, the upper limit for the pitch of the worm should be smaller than the outer diameter of the worm.

In Fig. 1, I have shown only one outlet slit at each of the covers 15a or 15b, through which the particles are discharged from the separating chamber. It is evident that in some cases it may be desirable to provide several outlet slits for the particles, as in the case of the slits 23 in Fig. 6, or the slits 28 in Fig. 7.

The sludge space 12a or 12b, or both, may be provided with openings which can be shut by covers or valves, and through which the separated particles can be discharged. Furthermore, special pockets or collecting vessels for the particles may be connected to these openings, and the openings can be closed by the valves, or the like, when the pockets are to be emptied or exchanged.

It is often desirable that the particles accumulated in a sludge space be discharged out of it continuously. This can be achieved by passing the discharge from the sludge space through a suitable mechanical device such as a filter or, when the particles are not difficult to separate, through an ordinary cyclone which has no moving parts. Such a cyclone may be connected to the sludge space and supplied from there with gas containing particles, the pressure of the gas thus being about equal to the inlet pressure in the separating chamber 1 of the separator. The cyclone purified gas, which has a degree of purity less than that of the purified gas from the sep-

arator, constitutes but a small portion of the separated gas quantity, and it may if necessary be led back to a nozzle in the gas pipe supplying the separator. In this case, the kinetic energy of the gas from the cyclone should be transformed into pressure energy, which may be done in any suitable manner. If the gas passes through the cyclone with moderate losses, the area in that part of the nozzle where the gas is reintroduced into the pipe supplying the separator, need only be slightly smaller than the area at the inlet 6 of the separator.

In separators having rotors which cannot be reinforced by pipes 26 or 27 (Figs. 6 and 7), for example, a separator as shown in Fig. 1, it may be necessary to introduce several supports to centre the worm, possibly along the whole of its length. The worm is, in fact, generally similar to a spiral spring, that is, rather weak transversally, and this may cause certain difficulties at high or critical speeds. Such supports may consist of spokes attached to the inner edge of the worm and to the shaft. The supports may be shaped in such a way and/or spaced at such a distance that a small elastic change of shape during the rotation can be permitted by them. In those cases where it is not necessary to consider any relative speed between the gas and the rotor at the gas outlet from the separating chamber, the spokes may be replaced, as shown in Fig. 5, by supporting ribs 21 extending along the entire length of the worm. The ribs will stiffen the rotor considerably, but if the critical rotational speed of the rotor need not be great, the ribs 21 may be divided into shorter lengths which are attached to each other.

As the coarsest sludge particles are thrown at a high speed against the pipe 2, the latter may be arranged so that it is easily replaceable, or it may be made of a durable material, or its surface may be provided with a protective coating.

The nature, temperature, etc. of the gas to be separated may make it necessary to protect the shaft bearings in some way, for instance, by enclosing them within seals, or by cooling the bearings and possibly the shaft as well.

I claim:

1. Apparatus for centrifugally separating particles from a fluid, which comprises a housing containing a separating chamber having an inlet for the mixture of fluid and particles and an outlet for the purified fluid, means for directing the mixture tangentially into the chamber through said inlet to cause the mixture to rotate around the chamber, a rotary helical worm in the chamber disposed substantially coaxially therewith and operable to discharge from the chamber particles suspended in the fluid, said mixture inlet being located near the outer edge portion of the worm, and said purified fluid outlet being located near the inner edge portion of the worm, and means for rotating the worm at a predetermined angular speed relative to the angular speed of particles suspended in the fluid adjacent the worm, to effect said discharge of the particles in a direction generally parallel to the rotation axis of the worm.

2. Apparatus as defined in claim 1, in which the pitch of the worm is smaller than the outer diameter of the worm.

3. Apparatus as defined in claim 1, in which the axial length of the worm is at least as large as the outer diameter of the worm.

4. Apparatus as defined in claim 1, in which the peripheral part of the worm extends along

11

said inlet but projects axially beyond at least one side of the inlet for a distance at least as great as the radial dimension of the worm from its inner edge to its outer edge.

5. Apparatus as defined in claim 1, in which said purified fluid outlet is displaced from the mixture inlet in the direction of the axis of rotation of the mixture in the chamber.

6. Apparatus as defined in claim 1, in which said last means rotate the worm in the direction of rotation of the mixture in the chamber and at a rate such that the peripheral speed of the worm is less than the speed of the mixture at the inlet, said outlet being displaced from the inlet in the direction of the axis of rotation, the pitch of the worm decreasing from the region of the inlet to the region of the outlet.

7. Apparatus as defined in claim 1, in which said last means rotate the worm in the direction of rotation of the mixture in the chamber and at a rate such that the peripheral speed of the worm is greater than the speed of the mixture at the inlet, said outlet being displaced from the inlet in the direction of the axis of rotation, the pitch of the worm increasing from the region of the inlet to the region of the outlet.

8. Apparatus as defined in claim 1, in which the ratio between the outer diameter and the inner diameter of the worm, as measured in a common plane at right angles to the axis of the worm, is less than 6 to 1 but greater than 1.5 to 1.

9. Apparatus as defined in claim 1, in which said last means rotate the worm in the direction of rotation of the mixture in the chamber and at a rate such that the peripheral speed of the worm is greater than the speed of the mixture at the inlet but less than the speed of the fluid at said outlet.

10. Apparatus as defined in claim 1, in which said chamber has a limit surface provided with discharge openings for particles separated from the fluid.

11. Apparatus as defined in claim 1, in which the chamber has two outlets for separated particles, one particle outlet being located at each side of the mixture inlet reckoning in the direction of the axis of rotation of the mixture in the chamber, one of said particle outlets being disposed near the outer edge of the worm and the other near the inner edge of the worm.

12. Apparatus as defined in claim 1, in which the chamber has a plurality of annular outlet openings arranged coaxially with the axis of rotation of the mixture in the chamber and at different radial distances from said axis, through which particles of varying separability are discharged from the chamber, easily separated particles being discharged through one of said annular openings located at a relatively great radial distance from said axis, and particles difficult to separate being discharged through an annular opening nearer said axis.

13. Apparatus as defined in claim 1, comprising also a receptacle for receiving particles separated in said chamber, the chamber having a plurality of particle outlets communicating with the receptacle and located at different radial distances from the axis of rotation of the mixture in the chamber, and means for inhibiting circulation of fluid from one of said particle outlets to another through the receptacle.

14. Apparatus as defined in claim 1, comprising also a receptacle for receiving particles separated in said chamber, the chamber having a plurality of particle outlets communicating with the recep-

12

tacle and located at different radial distances from the axis of rotation of the mixture in the chamber, and means for inducing a small circulation of fluid through the receptacle from a particle outlet located at a relatively small radial distance from said axis to a particle outlet at a greater radial distance from said axis.

15. Apparatus as defined in claim 1, comprising also a shaft in the chamber for rotating the worm, and means for supporting the worm on the shaft and shaped to offer only a small resistance to the movement of the fluid at said fluid outlet.

16. Apparatus as defined in claim 1, comprising also a shaft for rotating the worm, and turbine means for transmitting to the shaft energy from the speed of rotation and of translation of the fluid at said fluid outlet.

17. Apparatus as defined in claim 1, comprising also a shaft in the chamber for rotating the worm, and spokes in the form of wings for supporting the worm on the shaft and shaped as turbine blades.

18. Apparatus as defined in claim 1, comprising also a shaft for rotating the worm, and turbine means for transmitting to the shaft energy from the speed of rotation and of translation of the fluid at said fluid outlet, the turbine means including a generally ring-shaped rim of turbine blades rotating with the shaft, and an adjacent stationary rim of guide blades.

19. Apparatus as defined in claim 1, in which said last means rotate the worm about the axis of rotation of said mixture in the chamber, a receptacle for receiving particles separated in the chamber and communicating with the chamber at a greater radius from said axis than the purified fluid outlet, and means for preventing fluid from leaking to said fluid outlet from the receptacle.

20. Apparatus as defined in claim 1, in which said last means rotate the worm about the axis of rotation of said mixture in the chamber, a receptacle for receiving particles separated in the chamber and communicating with the chamber at a greater radius from said axis than the purified fluid outlet, there being a clearance space adjacent part of the rotating structure and extending between the fluid outlet and the receptacle, and means for creating across said clearance space a drop in pressure greater than that between the fluid outlet and the receptacle and acting to oppose leakage of fluid through said space from the receptacle to the fluid outlet.

21. Apparatus as defined in claim 1, comprising also a diffuser forming said outlet for the purified fluid and including a part rotating with the worm and a stationary part, said diffuser parts defining a generally annular slit coaxial with the axis of rotation of the worm and located at a radial distance from said axis which is at least as great as the radial distance from said axis to the outer edge of the worm.

22. Apparatus as defined in claim 1, comprising also adjustment means for varying the minimum area of said mixture inlet.

23. Apparatus as defined in claim 1, comprising also supporting members to which the ends of the worm are fixed.

24. Apparatus as defined in claim 1, comprising also a generally annular member rotatable with the worm and through which the purified fluid flows from the separating chamber, a second generally annular member rotatable with the worm and surrounding the first member in spaced rela-

tion thereto, said members defining an outlet from the chamber for particles separated in the chamber, and a receptacle for the particles communicating with said particle outlet along one end of said second annular member and also communicating with the chamber along the other end of said second member.

25. Apparatus as defined in claim 1, in which the chamber has near each end of the worm an outlet for the purified fluid, the chamber also having near at least one end of the worm an outlet for particles separated in the chamber, said particle outlet being located at a greater radial distance from the axis of rotation of said mixture in the chamber than the adjacent fluid outlet.

NORE EINAR BERGNER.
